H. R. WOODWARD

NOSTRIL EXPANDER

Filed Oct. 18, 1922

By

Inventor
Henry R. Woodward

Attorney

UNITED STATES PATENT OFFICE.

HENRY R. WOODWARD, OF WASHINGTON, DISTRICT OF COLUMBIA.

NOSTRIL EXPANDER.

Application filed October 18, 1922. Serial No. 595,294.

To all whom it may concern:

Be it known that I, HENRY R. WOODWARD, a citizen of the United States, residing at Washington, in the District of Columbia, have invented certain new and useful Improvements in Nostril Expanders; and I hereby declare that the following is a full, clear, and exact description thereof, reference being had to the accompanying drawings, which form part of this specification.

This invention is an improvement in nostril expanders to prevent snoring, such as shown in my Patent No. 1,077,574, of November 4, 1913.

The object of the present invention is to improve the expander shown in my aforementioned patent so that it will not have to clamp the cartilage of the nose to retain the expander in place, and instead to so form the expander that it will be securely retained in position in the nose, without discomfort to the wearer, by the engagement of portions of the expander with the fossæ of the nose (the slight depressions just inside the nose) whereby the expander will be comfortably and securely retained in position, and when it is desired to remove the expander from the nose, said portions can be readily disengaged from the fossæ.

A further object is to so form the nostril engaging portions of the expander that they will insure full passage of air even if the nostrils should be so large or so flexible that expanders shown in my aforesaid patent would be ineffective.

As stated in my aforesaid patent, many persons have nostrils which tend to collapse, thereby restricting or closing the air passages, and the principal use of my expander is to expand the nostrils or maintain them in expanded position so that ample air passages are maintained through the nose, and the wearer is not obliged to open his mouth to get an adequate air supply. The expanders, when so used, will prevent snoring. The expanders are also useful to athletes performing violent exercises, to ensure a full supply of air to the lungs through the nose.

I will explain the invention with reference to the accompanying drawings, which illustrate the improved expander, and in the

claims summarize the improvements where-in the present invention consists.

In said drawings:

Fig. 1 is a front elevation of the expander as applied to the nose, indicating by dotted lines the outline of the nose.

Fig. 2 is an end elevation of the expander looking inwardly.

Fig. 3 is a side elevation of the expander, indicating by dotted lines the outline of the nose.

Fig. 4 is a perspective view of the expander detached.

The expander is preferably made of a non-corrosive metal wire, but can be made of any suitable material which will hold its shape and be substantial enough to prevent collapse or partial collapse of the nostrils.

The expander has a central U-shaped portion, the legs of which extend on opposite sides of the middle cartilage of the nose, but do not press against the sides thereof (as they do in my Patent #1,077,574) and the front extremity of this central portion is bent downward as shown at 1, so that when this middle bend of the part is up against the end of the middle cartilage of the nose, the similar opposite members of the device extend upward and into the nostril cavities, as indicated in Figs. 1-3.

The inner or upper ends of each side 1^a of the U-shaped portion merges into one end of a small downwardly projecting ring-like bend 1^b which is adapted to engage a fossa of the nose to retain the expander in place. From the other ends of said ring the member continues upwardly and inwardly in a short straight portion 1^c, which merges into a loop 1^d which is approximately semi-circular, as shown. At the extremity of the loop 1^d the member terminates in a small bend 1^e, which cannot penetrate the skin or injure the nostrils.

The loops 1^d are formed of a size to fit comfortably and nicely within the nasal cavities, above the fossæ, and afford sufficient surface to comfortably support and distribute the pressure upon the nostrils.

In my aforesaid Patent #1,077,574, the loops are practically parallel with the side portions 1^c, but in my present invention the loops 1^d lie at an angle to each other and the vertical portions of the loops 1^d incline

outwardly, and the upper portions thereof incline inwardly (see Figs. 1, 2 and 4) so that the ends 1^e of the members are closer together than are the middle portions of 5 loops 1^a, as will be seen by reference to the drawings.

While my improved expander has some general similarity to that shown in my Patent #1,077,574, it differs therefrom in 10 three very important features; first, there is no contact between the sides 1^a of the U-shaped portion and the middle cartilage of the nose, and instead of such portion clamping the middle cartilage (as in my 15 Patent #1,077,574) in my present invention I avoid clamping or pinching of the middle cartilage, such clamping being very objectionable to some persons and also lessening the effective expansive flexibility of the expander. Second, the loops 1^d of my improved expander instead of inclining inwardly toward each other at their upper 20 sides, as they do in said patented construction, incline outwardly as viewed from above, (see Fig. 1) or below (Fig. 2), and these loops 1^d are relatively inclined at such an angle that when viewed from the front as in Fig. 2, they approximately form an oval or circle and will effectively prevent the nostrils however weak or flexible wholly collapsing, or closing against the cartilage, 25 and thus assure full passage of air.

Third, the expander is securely held in 30 position by the bends 1^b which engage the fossæ of the nostril cavities and the slight pressure on the inner sides of the nostrils on the loops 1^a will cause the rings 1^b to remain in engagement with the fossæ of the nose until the expander is disengaged therefrom by hand.

To place the expander in the nose the part 1 of the expander should be grasped with thumb and finger, and the loops 1^d inserted into the nostrils of the nose until the loop 45 1 is arrested by the cartilage, the expander will then be in the position illustrated in Figs. 1 and 3, and the bends 1^b will engage the fossæ of the nose very gently and hold the expander in proper position without dis- 50 comfort to the wearer.

The expander, when in place, will hold the nostrils open so that all the air required by

the lungs can be inhaled and exhaled through the nose, and the user's mouth will stay closed even when asleep. 55

What I claim is:

1. A nostril expander comprising similar opposite members and a connecting U-shaped portion, each side member having a part adapted to engage one of the fossæ of the 60 nose when the expander is inserted therein, and a comparatively large nostril supporting loop beyond the said part, the loop being inclined outwardly and upwardly and away from the opposite loop on the other member, and the free extremity of the loop being 65 of a form to prevent injury to the nostrils.

2. The herein described nostril expander having opposite side members connected by a U-shaped portion, each side member having a part at the end of the U-shaped portion 70 adapted to engage a fossa of the nose when the expander is inserted therein, and having a short straight portion extending from said part and merging into a loop, said 75 loop being inclined outwardly and upwardly and away from the like loop on the opposed member, and the upper portion of such loop curving inwardly and having its free terminal so formed as to prevent injury to the 80 nostrils, the upper portions of the loop inclining inwardly toward the opposed loop.

3. The herein described nostril expander having a central U-shaped portion and opposite side members extending from and forming a continuation of this U-shaped portion, each side member having a ring-like bend at its junction with the U-shaped portion adapted to engage one of the fossæ 85 of the nose when the expander is inserted 90 therein, and having a straight portion extending from such bend for a short distance and merging into a comparatively large loop; the loops on the opposite side members inclining outwardly and upwardly and 95 away from each other, and the upper portion of each loop curving inwardly and having its free terminal formed to prevent injury to the nostrils, substantially as described. 100

In testimony that I claim the foregoing as my own, I affix my signature.

HENRY R. WOODWARD.
